CLAIM

The ornamental design for a wristwatch, as shown and described.

DESCRIPTION

FIG. 1 is a front elevational view of a wristwatch showing my new design;

FIG. 2 is a back elevational view thereof;

FIG. 3 is a top plan view thereof;

FIG. 4 is a bottom plan view thereof;

FIG. 5 is a right side elevational thereof;

FIG. 6 is a left side elevational view thereof;

FIG. 7 is a front, bottom, right side perspective view thereof;

FIG. 8 is a back, bottom, left side perspective view thereof;

FIG. 9 is an enlarged front elevational view of the wristwatch of FIG. 1;

FIG. 10 is an enlarged top plan view thereof;

FIG. 11 is an enlarged bottom plan view thereof;

FIG. 12 is an enlarged right side elevational view thereof;

FIG. 13 is an enlarged left side elevational view thereof; and, FIG. 14 is an enlarged front, bottom, right side perspective view thereof.

The broken lines depict portions of the wristwatch that form no part of the claimed design. In FIGS. 9 and 12-14 the wristwatch is shown with a symbolic break in its length.
